UNITED STATES PATENT OFFICE.

THOMAS BAKER HUESTIS, OF BRISTOL, RHODE ISLAND, ASSIGNOR TO NATIONAL INDIA RUBBER COMPANY, OF BRISTOL, RHODE ISLAND, A CORPORATION OF RHODE ISLAND.

COATING MACHINE.

Application filed November 6, 1925. Serial No. 67,214.

This invention relates to a coating machine, more particularly to a machine for applying cement to the insoles of footwear articles.

5 In the manufacture of footwear articles, particularly in the manufacture of rubber or fabric and rubber footwear, it is necessary to apply a coat of cement to one side of the insole, the insole after drying being applied to a last with the cemented side out, the lower edges of the upper being then drawn over the insole and secured, and the usual filler sole and other parts being then applied. For many years it has been customary to cement the insoles manually, this operation requiring considerable time and labor, and unless the operator is careful the coating applied is not even and sufficient in quantity. More recently machines have been devised for accomplishing this result, but while more rapid than the hand operation they are open to numerous objections and are easily clogged owing to the viscous nature of the cement used, thereby requiring considerable time and labor in cleaning.

An object of my invention is to provide a simple, rapid, efficient and compact machine for applying coatings to sheet articles.

Another object is to provide an improved machine for applying cement to insoles for footwear articles.

Still another object is to provide a coating machine having an improved coating mechanism.

35 A further object is to provide a coating machine which can be readily dismounted for purposes of cleaning and repair and which will not readily clog in operation.

A still further object is to provide a machine in which the finished article is delivered in such position that the proper working of the machine may be readily determined.

The invention consists broadly in cooperating coating and feed rolls provided with means whereby an even, relatively thick coating may be applied, a reservoir for the coating material disposed to present the material to a relatively large area of the coating roll, a guide means for reversing the position of the coated article and returning it adjacent to its starting point in the machine.

For a detailed disclosure of the nature

and objects of the invention reference is had to the accompanying specification and drawings, in which latter,

Fig. 1 is a side elevation of the machine with parts broken away and in section;

Fig. 2 is a part sectional and broken-away view of the cementing mechanism;

Fig. 3 is an end view of the same with parts broken away;

Fig. 4 is a perspective of the cement trough or reservoir;

Fig. 5 is a broken perspective of the delivery conveyor and a cemented insole.

Fig. 6 is a perspective of an insole guide.

Fig. 7 is an enlarged view of a portion of the cementing roll; and

Fig. 8 is a section on the line 8—8 of Figure 1.

Referring to the drawings, the numeral 1 designates the base of the machine which is supported by the legs 2. Extending upwardly from the base 1 is a column 3 carrying at its upper end a table or support 4 upon which is mounted the drive mechanism. In the present instance the drive is from an electric motor 5, the shaft 6 of which is connected by a reduction gear mechanism 7 to a shaft 8 on which is mounted a sprocket 9 engaging the drive chain 10. This chain can be tightened by means of an idler sprocket 11 mounted on an arm 12 pivoted to the shaft 8 and adjustably secured in position at 13. It will be obvious that any other suitable form of drive may be employed.

Extending upwardly from the base 1 is a frame 14 in which is mounted the shaft 15 of a cementing roll 16 (see Figures 1, 3 and 8). The surface of the roll 16 is provided with a series of evenly spaced small projections 16' for a purpose to be later described. Loosely mounted on the shaft 15 is a sprocket 17 over which the drive chain 10 passes, and this sprocket may be rigidly connected to the shaft 15 by means of the known form of clutch 18 operable by the handle 19. Disposed above the cementing roll 16 is a cooperating idler or feed roll 20, the shaft 21 of which is mounted in the arms of a yoke 22 pivotally connected to the frame at 23. Extending upwardly from the yoke 22 is an arm 24 through the upper end of which loosely passes a rod 25 mounted on the frame 14. Surrounding the rod is a coiled spring 26 bearing at one end against

a nut 27 and at the other end against the arm 24, while in rear of the arm 24 a second nut 28 is threaded on the rod. It will be seen that by adjusting the nuts 25 and 28 the compression on the spring 26 and consequent pressure of the feed roll 20 against the cementing roll 16 can be varied. In order to drive the feed roll 20 in unison with the cementing roll a gear 29 is mounted on the shaft 15 of the cementing roll, which gear meshes with a second gear 30 carried on the shaft of the feed roll 20.

A second frame 31 extends upwardly from the base 1 and carries at its upper end cross pieces 32 to which is secured a table 33, this table being cut away at its middle as shown in Figure 2 to provide room for a feed conveyor 34. This conveyor passes over an idler roll 35 at one end, said roll being carried in the bearings 36 which are adjustable to tighten the belt by means of the set screws 37. At its opposite end the conveyor passes over a driving roll 38 (Figure 2) the shaft of which carries a gear 39 meshing with an intermediate gear 40, which latter in turn meshes with the gear 29.

Supported in inverted position on the frame 31 is a cement tank 41 provided with a discharge spout 42 governed by the valve 43. Disposed below the spout is a cement trough or reservoir 44 provided with an opening 45 in its top, into which the discharge spout 42 projects. The reservoir 44 is closed except adjacent its end opposite the opening 45 where it is provided with an opening 46 for the reception of the lower portion of the cementing roll 16. In order that the cementing roll may be immersed relatively deeply in the cement the reservoir 44 is provided with the arcuate bearing surfaces 47 at its sides which are adapted to closely engage the hardened bearing rings 48 at the ends of the cementing roll. The reservoir 44 is also provided with a cement control plate or scraper 49 (Fig. 8) for varying the quantity of cement withdrawn from the reservoir by the roll 16, this plate being adjusted by means of the set screws 50. Below the bearing surfaces 47 the reservoir 44 is provided with recessed bearing lugs 51 with which engage pins 52 carried on the arms of a yoke 53 pivoted to the frame 14 (Figs. 1 and 3). Extending downwardly from the yoke is an operating arm 54 to the lower end of which is pivotally connected a rod 55 loosely passing through a guide plate 56. Surrounding the rod is a coiled spring 57, the pressure of which may be adjusted by the nut 58. It will be seen that by this construction the reservoir 44 is yieldingly but closely held in contact with the cementing roll 16, and it can be instantly dismounted for purposes of cleaning or inspection. The tank 41 and reservoir 44 form a feed device of the well known "fountain" type, the level of the ce-

ment in the reservoir 44 remaining substantially constant and as it is removed therefrom to a point below the lower end of the spout 42 air can enter the spout and allow a flow of cement from the tank 41 to the reservoir. It will also be seen that by the construction of the opening 46 the cementing roll 16 is relatively deeply immersed in the cement. This not only insures a plentiful supply of cement to the cementing roll but by reducing the area of the roll which is exposed to the air it minimizes evaporation and consequent formation of partially dried cement upon the roll. Disposed in rear of the cementing roll is a curved guide 59 which cooperates with the curved end wall 60 of the reservoir 44 to provide a passageway into which the cemented insole is guided, and by the provision of the ridges 61 on the wall 60 and ridges 62 on the guide 59 the points of bearing of the insole on the walls of the passageway are reduced to a minimum so that friction caused by the cement sticking to the walls is also reduced. It will be seen that from the construction the insole is cemented on its bottom and as the end of the insole strikes the guide 59 the insole is bent around so that it is delivered at the bottom of the guide 59 with its direction reversed and with its position reversed so that the cemented side is uppermost.

From the guide 59 the insole passes on to a second conveyor 63, which is provided with the curved or arcuate supports 64, these supports reducing to a minimum the points of contact with the insole thereby preventing any excess of cement on the sides of the insole from causing it to stick to the conveyor. At its outer end the conveyor passes over an idler roll 65 mounted in the adjustable bearings 66. At its inner end the conveyor passes over a driving roll 67 (Fig. 3), on the shaft of which is a gear 68 meshing with a second gear 69, the latter having mounted on its shaft a sprocket 70 over which passes a chain 71 driven from the sprocket 72 on the end of the cementing roll shaft 15. At the delivery end of the conveyor 63 the cemented insoles 73 pass over a roll 74 and are delivered to any suitable receptacle or other conveyor.

In operation the insoles are fed on the conveyor 34 from the table 33 and are carried by the conveyor between the cementing roll 16 and the yielding driven feed roll 20. Due to the depth to which the cementing roll is immersed it receives a heavy coating of cement, the thickness of which can be varied by adjustment of the control plate 49. By reason of the projections 16' on the roll the insole is more easily fed between the rolls 16 and 20 and relatively thick coating on the insole is insured, since the projections 16' prevent the two rolls from exercising a squeezing action which would leave only a

relatively thin layer of cement on the insole. In addition such squeezing action would form a bank of cement at the point where the insole first meets the rolls, and as the 5 rear end of an insole passes this point the bank of cement would be transferred to the feed roll 20 with consequent marring and deposit of cement on the upper surface of the insole. As the insole issues from be- 10 tween the rolls with its lower side cemented its end engages the guide 59, and as before stated it is thereby bent or deflected so that as it issues from the lower end of the guide 59 its direction is reversed and its cemented 15 side is uppermost. As the insoles pass between the curved outer wall 60 of the reservoir and the guide 59 the cemented side of the insoles would tend to stick to the wall 60 but by the provision of the ridges 61 and 20 the ridges 62 on the guide 59 the bearing of the insole on the walls of the passageway is reduced to a minimum. In the same way the curved supports 64 on the conveyor 63 prevent sticking of the insole to the con- 25 veyor.

It will be seen that by the construction above described a very compact, simple and rapid machine has been devised. By reason of the return of the cemented articles adjacent to the feeding point the operator is able to readily determine whether the machine is operating properly by an inspection of the articles, and he can do this at all times without interrupting the process of 30 feeding soles to the machine. By reason of the close fitting of the cement reservoir 44 to the roll 16 and the relatively deep immersion of the latter in the cement an adequate supply of cement is insured, while at 35 the same time the exposure of cement to the atmosphere is reduced to a minimum. Should the operator desire to inspect or clean the reservoir 44 the latter can be instantly dismounted and easily cleaned.

With the above detailed disclosure of the invention numerous modifications will suggest themselves to those skilled in the art, and it is therefore not desired to limit the invention otherwise than as set forth in the 40 appended claims.

Having thus described my invention what I claim and desire to protect by Letters Patent is:

1. A coating machine comprising a coating roll having small projections thereon, a 45 cooperating yieldingly mounted feed roll, a reservoir for coating material partly surrounding said coating roll and extending upwardly on the discharge side of said roll, means for governing the supply of coating

material to the coating roll, and a curved guide forming with the outer wall of the reservoir a passageway for reversing the position of the coated article.

2. A coating machine comprising a coating roll having small projections thereon, a cooperating yieldingly mounted feed roll, a reservoir for coating material partly surrounding said coating roll and extending upwardly on the discharge side of said roll, 65 means for governing the supply of coating material to the coating roll, a curved guide forming with the outer wall of the reservoir a passageway for reversing the position of the coated article, the walls of said passageway being provided with means for reducing the friction between the coated article and said walls.

3. A coating machine comprising a coating roll, a cooperating feed roll, a reservoir for the coating material disposed below and partly surrounding the coating roll, said reservoir having curved side walls closely engaging the coating roll adjacent its ends, and means for yieldingly maintaining said 80 side walls in engagement with the coating roll.

4. A cementing machine for sheet articles comprising a feed conveyor, a cementing roll and a cooperating feed roll at the delivery end of said conveyor, said cementing roll being provided with a series of small projections, a cement reservoir having curved side walls closely engaging the ends of said cementing roll, means for yieldingly 90 maintaining the reservoir in contact with the cementing roll, a curved guide at the delivery side of said rolls for reversing the position and direction of the coated article, and a delivery conveyor adjacent said guide, 95 said conveyor being provided with means for maintaining the cemented article out of direct contact with the conveyor.

5. A coating machine comprising a conveyor for feeding sheet articles, cooperating rolls at the rear end thereof for applying coating to one face of each of said articles, a curved slide at the delivery side of said rolls contacting with the uncoated face of the articles emerging from between 105 said rolls and reversing the article and its direction, and a second conveyor at the discharge end of said slide for receiving the article therefrom and advancing it in the reverse direction.

Signed at Bristol, in the county of Bristol and State of Rhode Island, this 31st day of October, 1925.

THOMAS BAKER HUESTIS.
